UNITED STATES PATENT OFFICE.

HERMAN R. MULZER, OF EVANSTON, INDIANA.

RAIL-SPLICER

1,369,697.

Specification of Letters Patent. Patented Feb. 22, 1921.

Application filed June 22, 1920. Serial No. 390,772.

To all whom it may concern:

Be it known that I, HERMAN R. MULZER, a citizen of the United States, residing at Evanston, in the county of Spencer and 5 State of Indiana, have invented new and useful Improvements in Rail-Splices, of which the following is a specification.

This invention relates to a rail joint, the principal object of the invention being to 10 provide an overlapping connection between the bases of the two rails, the overlapping part being made of different lengths according to the weight of the trains which are to be run over the track.

15 Another object of the invention is to make the overlapping parts of the bases of tapered formation and to provide spike receiving openings in said overlapping portions for securing the rails to the ties.

20 Still another object of the invention is to provide the under overlapping portion with side flanges between which the top overlapping portion fits, thus preventing lateral movement of one part on the other.

25 This invention also consists in certain other features of construction and in the combination and arrangement of the several parts, to be hereinafter fully described, illustrated in the accompanying drawings 30 and specifically pointed out in the appended claims.

In describing my invention in detail, reference will be had to the accompanying drawings wherein like characters denote like 35 or corresponding parts throughout the several views, and in which:—

Figure 1 is a side view showing portions of a pair of rails connected together by my improved joint.

40 Fig. 2 is a longitudinal sectional view through the joint.

Fig. 3 is a horizontal section taken on line 3—3 of Fig. 1.

Fig. 4 is a cross section on line 4—4 of 45 Fig. 1.

Fig. 5 is a plan view, with parts broken away, of the rail which carries the under member of the overlapping joint.

In these views 1 and 2 indicate the rails, 50 the treads and webs of which are formed as usual. Rail 1 has its base provided with an extension 3 and the upper face of said extension slopes downwardly and outwardly from a point at its junction with the main 55 part of the base to the end of the extension

and said extension is provided with side flanges 4 which are of substantially the same height as the main part of the base. The formation of the extension is such as to provide a recess in its upper face, the bottom 60 of which slopes downwardly and outwardly.

The base of rail 2 has its under part cut away to leave a tapered portion, the under 65 face of which conforms to the bottom of the recess so that this part snugly fits in the recess in the extension 3. The formation of these parts forms a shoulder 5 at the inner end of the recess in the extension which is engaged by the reduced end of the base of 70 the rail 2 and a similar shoulder 6 is formed on the under face of the base of rail 2 to receive the small end of the extension. The overlapping portions of the bases may be bolted together by the bolts 7 and these 75 portions are also provided with registering holes 8 for receiving spikes so that the rails may be secured to the ties. The edges of the base of rail 2 engage the inner walls of the flanges 4 so that lateral play of the rails is 80 prevented. If the inclined faces of the bases should not exactly conform to each other spacer plates 9 may be located in the recess in the extension to true up the parts.

The ordinary fish plates 10 may be used 85 for connecting the webs of rails together.

The extension 3 may be made of considerable length when the track is to be used by heavy trains but for light traffic the extension need not be so long. The length of 90 this extension will also be varied to suit the conditions of the road bed.

As shown the upper faces of the bases at the joint are flat so that these parts are of extra strength and when the overlapping 95 parts are placed together they form a base of unusual strength.

The long overlapping bases will prevent the rail ends from sinking while the train is passing over them thus saving labor and tamping low joints and also avoid breaking of worn ties; and as these joints will hold the track level the locomotive will have more power as its drive wheels will have solid traction at all points along the track. The 100 level and solid track provided by my joint will also save wear and tear upon the rolling stock as well as the rails themselves and at the same time prevent jars and shocks to the 105 passengers.

It is thought from the foregoing description that the advantages and novel features of my invention will be readily apparent.

I desire it to be understood that I may 5 make changes in the construction and in the combination and arrangement of the several parts, provided that such changes fall within the scope of the appended claims.

What I claim is:—

- 10 1. A rail joint comprising an extension of the base of one rail, said extension having its upper face inclining outwardly and downwardly from its point of junction with the main base, flanges at the sides of the extension and a reduced part of the second rail base having an inclined under face for engaging the inclined face of the extension with its side edges fitting between the flanges.
- 15 2. A rail joint comprising an extension of the base of one rail, said extension having its upper face inclining outwardly and downwardly from its point of junction with

the main base, flanges at the sides of the extension and a reduced part of the second rail base having an inclined under face for engaging the inclined face of the extension with its side edges fitting between the flanges, said overlapping portions having spike receiving holes therein. 25

3. A rail joint comprising an extension 30 of the base of one rail, said extension having its upper face inclining outwardly and downwardly from its point of junction with the main base, flanges at the sides of the extension and a reduced part of the second rail base having an inclined under face for engaging the inclined face of the extension 35 with its side edges fitting between the flanges, said overlapping portions having bolt receiving holes therein and spacer plates 40 located between the overlapping parts.

In testimony whereof I affix my signature.

HERMAN R. MULZER.
